UNITED STATES PATENT OFFICE.

AUGUST SUNDH, OF HASTINGS-UPON-HUDSON, NEW YORK.

AUTOMATIC BLOCKING MECHANISM FOR STRIP-MILLS.

1,259,164.

Specification of Letters Patent. Patented Mar. 12, 1918.

Application filed April 6, 1916. Serial No. 89,268.

To all whom it may concern:

Be it known that I, AUGUST SUNDH, a citizen of the United States, residing in Hastings-upon-Hudson, in the county of Westchester and State of New York, have invented a new and useful Improvement in Automatic Blocking Mechanism for Strip-Mills, of which the following is a specification.

10 My invention relates to an improvement in automatic blocking mechanism for strip mills.

I have provided means for automatically blocking metal strips as they come from the 15 rolling mill, the strip itself by its entry between the mill rolls, setting into operation electrical devices for controlling the operation of the machine, but after the strip has once entered the rolling mill and the electrical 20 apparatus set into operation, the control of the electrical apparatus is automatically taken away from the strip; I have arranged this mechanism so that the strip at no time is in contact with the electrical device 25 for controlling the operation of the machine, consequently all danger of buckling of the strips from this source is avoided; my device requires no grounded circuits, which are always more or less troublesome, 30 and neither do I have any circuits passing through the strip; I have also provided means for automatically slowing down the driving mechanism for the block, to maintain the tension on the strip practically constant 35 throughout the blocking operation, this feature being of great advantage over the devices now in use, where the regulating of the tension on the strip is attended to by the operator, generally by means of a belt the 40 tension of which is varied by the operator; of course such an arrangement is not satisfactory as the operator has to judge when the tension of the strip is increasing to too high a degree, which is not easy and requires 45 a very experienced man; I have provided a block having a removable casing on which the strip is wound in the blocking operation; this casing together with the strip may be removed after the strip is blocked and another 50 casing put on and be blocking the next strip while the operator is removing the blocked strip from the first casing; of course this effects a great saving in time, as otherwise the blocking machine would have to be 55 stopped while the blocked strip is being re-

moved therefrom; it is of great advantage to pull the strip and casing off the block and remove the strip, over the old way of just simply pulling the strip off the block, which often causes buckling of the inside turns of strip; I provide guides from the mill to the block which will permit the escape of oil and water brought through the rolling mill by the strips, and also permit the operator to see the strip throughout the greater part of its travel so that should the strip buckle from any cause the operator will see it at once and cut off the strip back of the mill rolls before it has damaged the machine; the clamping of the strips to the block may be 70 regulated to suit various conditions, that is to say means have been provided which are adjustable and which clamp the strips to the block at the desired instant; and means have been provided to enable one to adjust 75 the machine to suit varying thicknesses of the strips.

All these and other advantageous features of my invention will be fully pointed out and described hereinafter.

Referring to the accompanying drawings illustrating my invention, wherein like characters of reference designate like parts throughout the drawings: Figure 1 is a plan view of the machine; Fig. 2 is an elevation, partly in section, showing the driving mechanism for the block, the block itself, the means for operating the same, and the governor for regulating the speed of the driving mechanism; Fig. 3 is an enlarged 85 view of the strip guiding mechanism shown in Fig. 1; Fig. 4 is a sectional elevational view of the mechanism shown in Fig. 3; Fig. 5 is an elevation of the block; Figs. 6 and 7 are cross sections through the block, Fig. 6 90 showing the block as it appears when a strip has just entered it, and Fig. 7 showing the block with the strip clamped and partly blocked; Fig. 8 is an elevation of the rolling mill viewed from the back and showing 95 the contact mechanism mounted thereon, which forms part of the mechanism for controlling the operation of the electrical devices embodied in my apparatus; Fig. 9 is an end view of the mill rolls; Fig. 10 is a 100 wiring diagram of the electrical features of the apparatus; Fig. 11 is a modification of the governor of Fig. 2, alternating current being used instead of direct; Fig. 12 is another modification of Fig. 2, the means 105

80

95

105

110

for controlling the speed of the block in this instance being a fluid means; and Fig. 13 shows diagrammatically the fluid means shown in Fig. 12.

5 Referring to the drawings in detail, I will first of all describe the construction of the block. It comprises an outer cylindrical shell or casing, 1, and an inner core 2, this core forming a magnet having magnet windings 3. The movable core of the magnet just mentioned, is designated 4, and is screwed through the outer end of the shell 1, and held in place in the shell by means of a lock nut 5. Mounted on this core and within 10 in the shell 1 is a coil spring 6, normally inert. A hinged section 7 is provided in the shell 1, for the purpose of admitting the strip to the inside of the shell. This hinged section or door, is normally held open by a spring 8, to insure that the section will be open when the strip reaches the block, and after the strip has entered the block and been clamped and the strip given a turn around the block the section 7 will be forced 15 closed, so that the periphery of the shell will be truly round and present an unbroken smooth surface to the strip being wound on it. Figs. 5 and 7 show clearly the appearance of the shell 1 when the strip designated 15 S has been wound thereon. The bore of the shell 1 is tapered, and the outside of the core 2 is correspondingly tapered, and the shell 1 is adapted to be slid on to the core 2, and it will thus be seen that when the magnet windings 3 are energized and the core 4 drawn inwardly, the strip will be clamped between the outer shell 1 and the core 2. In order that the inside of the block may be 20 rotated independently of the outside shell 1, I have provided a member 126 forming a support for the inner end of the shell 1 when the latter is in position on the core 2. This member 126 which is adapted for rotation at times, is mounted on the end of the bearing 25 12, the latter forming also a bearing for the core 2. A hand wheel 10 is carried by this member 126, this wheel carrying a spring actuated pin 127, which is adapted to be pressed into engagement with the face of an extension 128 formed on the bearing 12. The shell 1 and the member 126 are caused to 30 rotate as a unit by means of a key 9. When the shell 1 is first slid into place on the core 2, the hand wheel 10 is moved until the pin 127 enters an opening in the face of the extension 128, and as this extension is 35 stationary, the member 126 and the shell 1 are locked against further rotary movement. The parts are so constructed, that when the pin 127 enters the projection 128 the opening 7 in the block will be in place to receive the strip as it comes from the rolling mill. So soon as the magnet windings 3 are energized and the shell 1 drawn inwardly or 40 further on to the core 2 and the strip

clamped, the shell 1 will actuate an arm 129 carried on the pin 127 and move the same upwardly together with the pin 127. The withdrawal of the pin 127 from the extension 128 of the bearing 12 will permit the shell 1 and part 126 to rotate, and as the shell 1 and core are now fastened together by reason of the shell 1 having been drawn on to the core 2 far enough to clamp the strip between them the whole block will be free to rotate 70 as a unit. The spring 6 is provided for the purpose of insuring that the shell 1 will be out of engagement with the core 2 at such times that the magnet windings are not energized. A stationary pole piece 11 forms one core of the magnet formed by the core 2 and extends through the bearing 12 formed in a standard 13 which is a part of the bed of the machine, and a bearing 24, likewise formed in a standard 25 which is on the bed 80 of the machine, and has keyed thereon a clutch member 14, which is adapted to be actuated into position to engage a corresponding clutch member 15 on the face of a large gear 16, which gear is also keyed on the shaft 11, this latter gear being in mesh with and driven by a small gear 18 on the armature shaft of the electric motor 17. The clutch member 14 is adapted to be actuated into engagement with the clutch member 15 85 by means of a foot pedal 19 carried on a bracket 20 secured to the standard 13, and having a slot and pin connection with one arm 21 of a bell crank lever, this arm being directly connected to the clutch member 14. 90 By depressing the foot pedal 19 the member 14 is forced to the left to engage the clutch member 12. The other arm 22 of the bell crank forms a foot pedal, the depressing of which will cause the clutch members to be 95 disengaged, and if the pedal be depressed sufficiently it will bring one part 14' of a friction brake into engagement with the face of the bearing 12, to stop the block, the member 14' being keyed on the shaft 11. 100 Mounted on the end of the shaft 11 opposite to the gear 16 is a beveled gear 26 meshing with another beveled gear 27, which latter operates a centrifugal governor G. This 105 governor is of the usual type of centrifugal governors, having fly balls 28 which are connected by links to a collar 29 which is mounted on a standard or spindle 30 which carries the balls 28 and their connected parts, etc. This collar 29 is connected to mechanism hereinafter to be described, which 110 mechanism controls the speed of the motor 17 so that the latter will maintain a practically constant tension on the strip while it 115 is being blocked.

120 Referring to Figs. 1, 3 and 4, the guiding means for the strip will be described. These means comprise in part, two guiding members, an upper and a lower, designated 31 and 32, respectively. The upper guide is 125 130

mounted for partial rotation about a shaft 33 secured in suitable supports 34 and 35 carried on the bed of the machine. The guides, both upper and lower are made in 5 grill form, for part of their length, this grill construction serving the double purpose of enabling the operator to see the strip in its passage through the guides, and permitting the escape of the oil and water 10 which may be carried by the strip as it comes from the rolling mill. The lower guide 32 is adapted to be swung into and out of operative position about the shaft 33'; both guide members being moved to operative 15 position, that is to say, into engagement with the face of the block, manually, and withdrawn from operative position automatically. The mechanism for operating the guide members comprises two pairs 20 of arms 36 formed, or which may be formed integral with the guiding members 31 and 32, these arms being connected by links 37 to a lever 38, offset from the guides and pivoted at its lower end to an extension 39 25 formed on the standard 35. By merely moving this lever to the left, as viewed in Fig. 4, the guides are moved to operative position, with their ends adjacent the face of the block. To actuate the guides to inoperative 30 position, I have provided a magnet 40 carried on the support 39, the core of this magnet being secured to a cross piece 41, this cross piece forming a connection of the lever 38 to both sets of links 37. It 35 will be seen that movement of the core of the magnet 40 will cause the lever 38 to be moved to the right, and the guides will be withdrawn from operative position, the full line position of Fig. 4, to inoperative position 40 as shown in dotted lines in the same figure.

Extending through the upper guide member are screws 51, 51 and 52, 52, these screws limiting the movement of the guides toward each other. The lower guide member 32 is provided at its end adjacent the block, with a hinged section 53. This section is adapted to be swung in upward position as shown in dotted lines in Fig. 4 when the 50 guide is withdrawn from the face of the block, being assisted in this movement by a spring 54. This section by thus swinging upwardly allows the lower guide member to be simply swung around its pivot, instead of 55 having to be retracted also to clear the face of the block. When the guide members are being adjusted to operative position, the end of this section 53 is engaged by the upper guide member by the screws 52, 52 and the 60 section forced downwardly, until when the guides are in full adjusted position, the section 53 is aligned with the rest of the lower guide member.

Guide members 42 and 43 are provided 65 for the strips, adjacent the rolling mill, and

between it and the end of the guides just described, the two sets of guiding members forming a continuous path for the travel and guidance of the strip from the rolling mill to the face of the block. Secured to 70 the end of these guides and in engagement with the mill rolls are two steel strips, 44 and 45, these strips being chamfered to a knife edge, and held in firm engagement with the face of the mill rolls by means of 75 springs 46 and 47. These members 44 and 45 are provided for the purpose of scraping the strips from the mill rolls as they come through the mill. The guides 42 and 43, together with the strips 44 and 45 and 80 strips 46 and 47 are movable across the face of the rolling mill, by means of screw threaded shafts 48 passing through the ends of the guides. These shafts of which there are two, one for the member 42 and one for 85 the member 43, are carried in the standard 35 and are adapted to be rotated therein, but to have no longitudinal movement, by means of members 49 to cause the guide members 42 and 43 to be moved into any 90 desired position across the face of the mill rolls. The guides 42 and 43 and knife strips 44 and 45 are of a less width than the guide members 31 and 32, and are constructed to have the lateral movement just described. 95 in order that they may always be in position to scrape the strips from the mill.

The support 35 for the guiding members described is pivoted at 137, so that the whole guiding mechanism may be swung to one 100 side about this pivot to give access to the mill rolls.

I will now describe the mechanism whereby I control the energization of the block, to cause the same to grip the strip, and 105 whereby I automatically cause my guiding mechanism to be withdrawn from the face of the block, after the strip has been so gripped. Referring first of all to Figs. 8 and 9, contact mechanism is shown secured 110 to the upper part of the rolling mill. This mechanism comprises a rod 57 extending across the mill and a short distance above the upper roll, and secured to the ends of the mill. Mounted on this rod is a member 115 58 adapted to be moved along the rod 57 and held in any desired position on the said rod by means of screws 59, 59. Affixed to this member, but insulated therefrom is a contact 60. Pivoted connected to the lower 120 part of the member 58 is a switch arm 61, this switch arm carrying a tip 62 constantly engaging the upper surface of the mill roll 56, this engagement being insured by a spring 64, mounted on the switch arm and 125 between it and the member 58. The closing of contacts 60 and 63 by reason of the mill roll 56 being raised, due to the entry of the strip into the rolling mill, closes a circuit for one of the windings 76 of a doubly 130

wound magnet, to set into operation certain mechanism now to be described. Carried on the end of the mill roll 56 and keyed thereto is a gear 72. Secured to the lower end of the 5 movable core 68 of the magnet 69 is a lever 66, this lever being pivoted at its other end at a point 65 at any convenient place at the end of the rolling mill. This lever carries a gear 67 adapted to rotate thereon and being at all times in mesh with a rack 70. This 10 rack is mounted on the end of the mill and adapted to move longitudinally in guides 71; the extreme outward movement of the core 68 of the magnet 69 is limited by a 15 screw 75'. Now when the winding of the magnet 69 is energized by closing of the contacts 60 and 63, the core 68 will be pulled inwardly carrying with it the lower end of the lever 66, and the gear 67, until the latter 20 meshes with the gear 72 carried on the end of the mill roll 56. As the mill roll at this time will be rotating, the gear also will be set into motion, and as it is in mesh with the rack 70, the latter will be moved upwardly, as viewed in Fig. 9.

Referring now to Fig. 10, I will trace the various circuits therein shown, and describe the function of these circuits and their effect on the operation of the machine. The 30 source of power for all of the circuits shown is designated S', and is controlled by a main line switch 75. In the following description the main line switch 75 is in closed position. The motor circuits are controlled by a 35 manually operated switch M, which is mounted in any convenient position on the machine, so as to be within easy reach of the operator. Assuming the lever M moved to the right as viewed in Fig. 10, with an arm 40 107 carried by said lever engaging a contact 108 and an arm 104 also carried by said lever engaging contact 102. The armature circuit for the motor may now be traced as follows: From the plus side of the line, 45 through conductors 86, 100, 101, contact 102, arm 104, conductor 105, through the motor 17, conductor 106, arm 107, contact 108, conductor 109, and out the minus side of the line. The field circuit of the motor may be 50 traced as follows: from the plus side of the line, through conductors 86, 92, field 98, conductor 94, contact 97 carried on an arm A controlled by the governor G, contact segment 98, conductor 99, and out the minus side 55 of the line. The motor now starts to rotate and is brought up to desired speed. Rotation of the motor, however, at this time merely rotates the core 2 of the block, as by reason of the structure already described 60 herein, the core 2 is not at this time engaged by the shell 1, and the latter is prevented from having any movement anyway by reason of the pin 127. A strip may now be fed to the rolling mill, and at once the roll 56 65 will be raised sufficiently to cause the con-

tacts 60 and 63 to close. Closure of these contacts first of all closes the circuit to the winding 76 of the magnet 69, this circuit being traced as follows: From the plus side of the line, conductor 84, through the winding 76, contacts 63, 60, conductor 85 to the minus side of the line. Closing of this circuit will energize the magnet 69 and the same will pull up its core 68 to bring the gear 67 into engagement with the gear 72 70 on the end of the mill roll. The gear 67 will thereby be rotated, and the rack 70 be moved upwardly to bridge contacts 73 by a bridge piece 74 carried on the upper end of the rack 70. Bridging of these contacts 73 75 closes a circuit to a winding 77 of a magnet 78, this circuit being traced as follows: From the plus side of the line, conductor 86, winding 77, conductor 87, lower contact 73, bridge piece 74, upper contact 73, conductors 85 and 89 and out the minus side of the line. As the winding 77 of the magnet 78 is energized it pulls up its core, carrying with it the arm 79 which arm carries a pair of contacts 80 and 81, these contacts being now in engagement with fixed contacts 82 and 83. With these contacts in engagement we find a circuit closed for another winding 114 of the magnet 78, this winding being wound in the same direction as the winding 77. This circuit may be traced as follows: From the plus side of the line, through conductors 86, 100, 101, through contacts 80, 81, 83, field 114, conductor 115, a contact 112 carried by the lever M, through contact 111, which the contact 112 engages by reason of the lever M being in operative position, conductor 116, winding 113 of the magnet 69, this winding being wound oppositely to the winding 76 of this magnet, and by conductors 85 and 99 to the minus side of the line. We find another circuit closed also by reason of the arm 79 having been moved to operative position, this is the circuit for the winding of the block. Up to this time it is to be remembered the inside of the block has been merely rotating idly. The various electrical devices are so timed that at the instant the winding for the block, the circuit for which is now to be traced, is energized, the strip 110 will have reached the block and entered therein the required distance. The circuit for the block is as follows: From the plus side of the line, through conductor 86, contacts 80 and 82, conductor 88, collector ring 115 120 89 carried on the end of the shaft 11, winding 3 of the block, collector ring 90, conductors 91, 85 and 99, to the minus side of the line; simultaneously with the establishment of this circuit just traced, a circuit for the 125 magnet 40 to cause the same to withdraw the guides from the face of the blocks is established, this circuit being in parallel to the circuit of the block winding and traced as follows: from the plus side of the line, 130

through conductor 86, contacts 80 and 82, conductors 88, 110, winding W of the magnet 40, conductors 91, 85, 99, to the minus side of the line. We now have the strip 5 clamped to the block by reason of the winding 3 being energized and the shell 1 drawn inwardly on to the block, the guides withdrawn and the strip being blocked. In order that I may keep the winding of the 10 magnet 78 alive so that the arm 79 will be in operated position to close the circuit to the winding of the block, I provide the two windings 77 and 114, the latter being held closed, or rather the circuit for the latter 15 being held closed, so long as the lever M is in operated position. The other winding 77 of this magnet is dead, as so soon as the winding 113 of the doubly wound magnet 69 received current by reason of the arm 79 20 of the magnet 78 being moved to operated position, the magnet 69 was deenergized and dropped its core, thus breaking the circuit of the winding 77 at the contacts 73. Thus it will be seen that although the contacts 60 25 and 63 will remain closed so long as the strip is between the mill rolls, their function is destroyed, or neutralized by the energization of the winding 113. In order to be able to adjust the parts just described, 30 that is in order to time them properly so that the block will be energized at the right instant when the strip enters it, I have provided the screw 75' at the bottom of the core 68 and the screw 136 at the bottom of 35 the core of the magnet 78. The movement of these cores may therefore be regulated so that they will perform their respective functions in the proper time to clamp the strip as it enters the block.

40 The initial rotation of the motor causes the governor balls 28 to fly out, and by reason of their connection to the arm A the arm A will be forced down to insert some of the resistance 95 in the field circuit of the 45 motor to weaken the same, but as the roll of strip on the block increases in diameter, the strip will tend to hold back the motor, and the governor balls 28 will drop, the arm A will be raised and some of the resistance 95 50 cut out of the field circuit of the motor, and the latter will slow down accordingly. It will thus be seen that automatically I slow down the motor as the diameter of the roll of strip being blocked increases, and consequently the tension on the strip will automatically be maintained practically constant.

55 When the strip has been completely blocked, the lever M is moved again to center position and the circuit for the motor as well as the circuit to the winding of the block will be broken and the motor and block will come to rest. If desired the foot pedal 22 may be depressed sufficiently in 60 disconnecting the clutch 14 from the clutch 65

member 15 to bring the brake member 14' into action to stop the apparatus more quickly.

The modification of the governor arrangement as shown in Fig. 11 is the same in operation as that already described, alternating current being used instead of direct, the arm A in this instance controlling resistance R in the circuit of the motor 17. The effect on the motor and strip is the same 75 as with the other governor.

In Figs. 12 and 13, I show a still further modification of the speed controlling mechanism for the block, in this instance the speed of the block being regulated, instead of the 80 speed of the motor. In these figures the gear 18 on the motor shaft meshes with a large hollow gear 120, this gear being carried on the shaft 11. Carried within this large gear are gears 121 and 122, meshing 85 with each other, the gear 122 being keyed to the shaft 11. The gear 120 is filled with a fluid, oil for instance, and the whole forms a fluid means for transmitting the power from the motor shaft to the shaft 11 to rotate the block. The action of this mechanism is controlled by valve mechanism 123, and when it is desired that the shaft 11 be rotated, the valve 123 is moved into position to lock the fluid within the gear 120, 90 thus forming a practically rigid connection from the shaft of the motor to the shaft 11 of the block. Movement of the valve mechanism 123 is controlled by a collar 124, this collar being on the shaft 11 and movable 95 longitudinally thereof, by means of a bell crank lever 125, one end of this bell crank lever being connected to the collar 124, and the other end to the collar 29 on the spindle of the governor G. Now it will be seen that 100 when the tension on the strip becomes sufficiently great to slow up the motor and the governor balls drop, the lever 125 will be actuated to move the valve 123 into position to allow the fluid within the hollow gear 120 105 to bypass, in other words there will be a slippage between the shaft 11 of the block and the motor shaft. The tension on the strip will therefore be maintained practically constant during the entire blocking 110 of the strip.

115 It will be seen from the foregoing description that I have provided a blocking mechanism which is practically automatic throughout its entire operation, and which is 120 capable of being adjusted to handle strips of varying thicknesses, and one in which I may vary the instant at which the strip will be attached to the block. Also that I have provided means whereby the strip automatically 125 sets into operation the mechanism for blocking the strip, but which mechanism after being once set into operation is automatically taken away from the control of the strip; also it will be seen that I have 130

provided means automatically to take care of the tendency of the tension on the strip to be increased as the diameter of the roll of strip on the block increases.

5. I appreciate that others skilled in the art of strip blocking, might make various changes in my apparatus without departing from the spirit and scope of the invention, and I desire therefore not to be limited to 10 the precise details and arrangement of parts herein shown.

What I claim and desire to have protected by Letters Patent of the United States is:—

1. In a blocking device adapted to wind a 15 strip coming from a strip mill, the combination of means for driving the block, and a governor driven by said block driving means adapted to regulate the speed of the block to maintain a practically constant tension on 20 the strip as it is being wound on the block.

2. In a blocking device adapted to wind a strip coming from a strip mill, the combination of means for driving the block, and a centrifugal governor adapted to control said 25 driving means to drive the block at a speed to maintain a practically constant tension on the strip as the virtual diameter of the block increases.

3. In a blocking device adapted to wind 30 a strip coming from a strip mill, the combination of means for driving the block at a predetermined speed as the strip enters the block, and a governor controlled by the speed of the block driving means adapted to slow 35 down the driving means as the virtual diameter of the block increases, thereby maintaining a practically constant tension on the strip throughout the blocking operation.

4. In a blocking device adapted to wind a 40 strip coming from a strip mill, the combination of an electric motor for driving the block at a predetermined speed as the strip enters the block, a speed controller for said motor, and a speed governor driven by 45 said motor and adapted to control said speed controller to thereby maintain a practically constant tension on the strip throughout the blocking operation.

5. In a blocking device adapted to wind a 50 strip coming from a strip mill, the combination of an electric motor for driving the block at a predetermined speed as the strip enters the block, a speed controller for said motor, a centrifugal governor regulating 55 said speed controller and controlling the same to maintain a practically constant tension on the strip throughout the blocking operation.

6. In a blocking device adapted to wind 60 a strip coming from the strip mill, the combination of an electric motor for driving the block, a regulating device in the circuit of the motor, a speed governor driven by the motor and controlling said regulating device 65 to vary the speed of the motor driving the

block thereby to maintain a practically constant tension on the strip throughout the blocking operation.

7. In a blocking device adapted to wind a strip coming from the strip mill, the combination of an electric motor for driving the block, a regulating device in the circuit of the motor, and speed controlled means to control said regulating device to vary the speed of the block driving motor in accordance with the tension on the strip being blocked. 75

8. In a blocking device adapted to wind a strip coming from a strip mill, the combination of an electric motor for driving the block, a rheostat in the circuit of said motor, a speed governor driven by the motor and controlling said rheostat to decrease the speed of the motor as the virtual diameter of the block increases during the blocking operation. 85

9. In a blocking device adapted to wind a strip coming from a strip mill, the combination of an electric motor for driving the block, a rheostat in the field circuit of said motor, a speed governor controlling said rheostat to decrease the speed of the motor as the virtual diameter of the block increases during the blocking operation. 90

10. In a blocking device adapted to wind a strip coming from a strip mill, the combination of an electric motor for driving the block, a rheostat in the field circuit of said motor, a speed governor driven by the motor for controlling said rheostat to vary the resistance of the field circuit of the motor to vary the speed of the motor in accordance with the tension on the strip to maintain a practically constant tension on the motor throughout the blocking operation. 95

11. In a blocking device adapted to wind a strip coming from a strip mill, the combination of means for driving the block to wind the strip under tension, a speed governor driven by the driving means in constant ratio to the speed of the block, and adapted to regulate the speed of the driving means to maintain a practically constant tension on the strip throughout the blocking operation. 110

12. In a strip mill, the combination of rolls for rolling the strip, blocking mechanism embodying a rotatable block on which the strip is adapted to be wound, a contact device operated by the mill rolls, a circuit for the block controlled by said contact device, to cause the strip to be attached to the block as it reaches the block. 115

13. In a strip mill, the combination of rolls for rolling a strip, blocking mechanism embodying a rotatable block on which the strip is adapted to be wound, a device operated by the mill rolls as the strip enters between the mill rolls and timed with the feeding movement of the strip to cause 120

the strip to be attached to the block as the strip enters the block, means to attach the strip to the block, and means to render said mill-roll-operated device inoperative after 5 the strip has been attached to the block.

14. In a strip mill, the combination of rolls for rolling a strip, blocking mechanism embodying a rotatable block on which the strip is adapted to be wound, and means 10 to cause the strip to become attached to the block, said means being operative only until the strip has become attached to the block.

15. In a strip mill, the combination of rolls for rolling a strip, blocking mechanism embodying a rotatable block, adapted to wind a strip coming from the strip mill rolls, a device operated by the mill rolls to cause the strip to be attached to the block when the strip reaches the block, said device 20 being operative from the time the strip enters the mill rolls, and means to render said device inoperative after the strip has been attached to the block.

16. In a strip mill, the combination of 25 rolls for rolling a strip, a blocking mechanism embodying a rotatable block, adapted to wind the strip coming from the strip mill rolls, a device operated by the mill rolls immediately when the strip is sent 30 through the rolls and continues the operation and causes the strip to be attached to the block when the strip reaches the block, and constructed to discontinue its operation after the strip becomes attached to the block, 35 and means acting independently thereof to hold the strip attached to the block during the winding of the strip.

17. In a strip mill, the combination of 40 rolls for rolling a strip, a blocking mechanism embodying a rotatable block adapted to wind the strip coming from the strip mill rolls, a device operated by the mill rolls to cause the strip to be attached to the block when the strip reaches the block, means for 45 rendering said device inoperative thereof, and independent means to hold the strip attached to the block after the first means has been rendered inoperative.

18. In a strip mill, the combination of 50 rolls for rolling a strip, a blocking mechanism embodying a rotatable block adapted to wind a strip coming from the strip mill, a device operated by the strip mill rolls, means to hold said device in position to be 55 so operated at the instant the strip enters the mill rolls, means operated thereby to clamp the strip to the block, and adjustable means operable to time the operation of the strip clamping means by the device operated 60 by the strip mill rolls so that the strip clamping means will be actuated at the instant the strip reaches the block.

19. In a blocking device adapted to wind 65 a strip coming from a strip mill, the combination of a device operated by the strip

mill, comprising a switch operated by the mill rolls, an electro-magnet operated by said switch, mechanism controlled by said magnet, and means controlled by said mechanism for causing the strip to be attached 70 to the block when the strip reaches the block.

20. In a blocking device adapted to wind a strip coming from a strip mill, the combination of a device operated by the strip mill, comprising a switch operated by the strip mill rolls at the instant the strip enters 75 therein, an electromagnet operated by said switch, mechanism controlled by said magnet, and means controlled by said mechanism for causing the strip to be attached to 80 the block when the strip reaches the block.

21. In a blocking device adapted to wind a strip coming from a strip mill, the combination of a device operated by the strip mill, comprising an electric switch operated 85 by the mill rolls, an electromagnet operated by said switch, mechanism controlled by said electromagnet and operated by the mill, and means controlled by said mechanism for causing the strip to be attached to the 90 block when the strip reaches the block.

22. In a blocking device adapted to wind a strip coming from a strip mill, the combination of a block, a switch operated by the strip mill, an oppositely wound double 95 wound magnet, said switch controlling one winding of said electromagnet, means for rotating the block, manual means for controlling said driving means and the other winding of said electromagnet, a block 100 winding to cause the strip to be attached to the block, means controlled initially by the energization of the first named magnet winding to close a circuit to said block winding, the energization of the second winding 105 of the double wound electromagnet to render said means inoperative, and means to maintain the circuit closed to the block winding after the first named magnet winding controlled means has been rendered inoperative. 110

23. In a blocking device adapted to wind a strip coming from a strip mill, the combination of a rotatable block, electro-magnetic means for operating said block to cause 115 the strip to be attached to the block, a device embodying an electric switch operated by the mill, an electro-magnet operated by said switch, mechanism controlled by said electromagnet and operated by the mill, and a 120 switch controlled by said mechanism to close a circuit for the electro-magnetic block operating means.

24. In a blocking device adapted to wind a strip coming from a strip mill, the combination of a rotatable block, electro-magnetic means for operating said block to cause 125 the strip to be attached to the block, a device embodying an electric switch, operated by the mill, an electromagnet operated by said 130

- switch, mechanism controlled by said electromagnet and operated by the mill, a switch controlled by said mechanism to close a circuit for said electromagnetic block operating means, and means to cause the mechanism operated by the mill to be rendered inoperative at the instant the strip is attached to the block.
25. In a blocking device adapted to wind a strip coming from a strip mill, the combination of a rotatable block, a cylinder adapted to slide over said block, means to attach the strip to the block, means to hold said cylindrical cylinder from rotating, initially, and means to cause said cylinder to rotate with the block after the strip has been attached to the block.
26. In a blocking device adapted to wind a strip coming from a strip mill, the combination of a rotatable block comprising a cylinder with a longitudinal slot to permit the strip to enter said cylinder, said cylinder being adapted to slide on the block, a bearing for said cylinder, and means to cause said cylinder and bearing to rotate as a unit after the strip has entered the cylinder.
27. In a blocking device adapted to wind a strip coming from a strip mill, the combination of a rotatable block, a cylinder adapted to slide over said block, means to hold said cylinder stationary while the block is rotating and means to cause said cylinder to rotate with the block.
28. In a blocking device adapted to wind a strip coming from a strip mill, the combination of a rotatable block, a cylinder adapted to slide over said block, means to hold said cylinder stationary while the block is rotating, and means automatically operable to cause said cylinder to rotate with the block.
29. In a blocking device adapted to wind a strip coming from a strip mill, the combination of a rotatable block, means to drive the block, a bearing for said block, a support for said bearing, a cylinder adapted to slide over said block, means to hold said cylinder stationary while the block is rotating, a bearing for said cylinder, a support for said bearing, and means to engage the cylinder and the rotatable block to cause the two to rotate as a unit.
30. In a blocking device adapted to wind a strip coming from a strip mill, the combination of a rotatable conical block, means to drive the block, a cylinder having a conical bore corresponding with the conical rotatable block, said cylinder being adapted to slide over said block, means to prevent rotation of said cylinder, and means engaging the conical rotatable block and the conical cylinder and cause the two to rotate as a unit.
31. In a blocking device adapted to wind a strip coming from a strip mill, the combination of a conical rotatable block, means to drive the block, a winding in said block, a cylinder having a conical bore to fit the conical block, an armature in the block connected with said cylinder, and means to energize the winding of the block to cause the cylinder and block to rotate as a unit.
32. In a blocking device adapted to wind a strip coming from a strip mill, the combination of a conical rotatable block, means to drive the block, a cylinder having a conical bore, and means to actuate the cylinder to clamp the strip coming from the strip mill between the conical bore of the cylinder and the conical part of the block.
33. In a blocking device adapted to wind a strip coming from a strip mill, the combination of a conical rotatable block, means to drive the block, a winding for said block, a cylinder having a conical bore, and means to energize the winding in the block to attract the cylinder and clamp the strip coming from the strip mill, between the conical part of the cylinder and the conical part of the block.
34. In a blocking device adapted to wind a strip coming from a strip mill, the combination of a conical rotatable block made of magnetic material, a winding for said block, a cylinder having a conical bore and made of magnetic material, an armature connected with said cylinder, and means to energize the winding of the block to attract the armature and the cylinder to clamp the strip coming from the strip mill, between the conical part of the cylinder and the conical part of the block.
35. In a blocking device adapted to wind a strip coming from a strip mill, the combination of a rotatable block, a winding for said block, means to energize said winding as the block is rotating, said block being conical, a cylinder having a conical bore and adapted to slide on said block, a strip mill controlled device, said device being adjustable and adapted to close a circuit for the winding in the block, to cause the conical cylinder to clamp the strip between the conical surface of the block and the conical surface of the cylinder when the strip reaches the block.
36. In a blocking device adapted to wind a strip coming from a strip mill, the combination of a rotatable block, a cylinder for the strip to be wound on and adapted to slide over the block, means to prevent said cylinder from rotating until the strip has entered the block, and means to cause said cylinder to rotate with the block after the strip has entered the block, and means to free said cylinder from the block after the strip is wound on the cylinder to allow the cylinder and the strip to be withdrawn from the block.
37. In a blocking device adapted to wind a strip coming from a strip mill, the combination of a rotatable block, a winding for said block, a cylinder having a conical bore to fit the conical block, an armature in the block connected with said cylinder, and means to energize the winding of the block to cause the cylinder and block to rotate as a unit.

a strip coming from a strip mill, the combination of a rotatable block, a cylinder adapted to slide over the block, a longitudinal opening in said cylinder for the strip to enter, means to prevent said cylinder from rotating until the strip has entered through the said opening, means to cause said cylinder to rotate with the block thereafter, and means to free the cylinder from the block to allow the cylinder and strip to be withdrawn from the block after the strip has been blocked.

38. In a blocking device adapted to wind a strip coming from a strip mill, the combination of a rotatable block, a cylinder adapted to slide over the block, a longitudinal opening in said cylinder for the strip to enter, means to prevent said cylinder from rotating until the strip has entered through the said opening, means to automatically cause said cylinder to rotate with the block thereafter, and means to free the cylinder from the block to allow the cylinder and strip to be withdrawn from the block after the strip has been blocked.

39. In a blocking device adapted to wind a strip coming from a strip mill, the combination of a rotatable block, and a cylinder for the strip to be wound on, means to permit the end of the strip to enter between the rotatable block and said cylinder, said cylinder being adapted to be slid over the block, and adapted to be manually withdrawn from the block after the strip has been wound thereon.

40. In a blocking device adapted to wind a strip coming from a strip mill, the combination of a rotatable block, a cylinder for the strip to be wound on and adapted to be slide over the block, and also adapted to be withdrawn from the block with the wound strip thereon, a longitudinal slot in said strip adapted to be closed up by the pressure of the strip in the blocking operation.

41. In a blocking device adapted to wind a strip coming from a strip mill, the combination of a rotatable block, a cylinder open at one end, and with a longitudinal slot for the strip to enter into the block, said cylinder adapted to be manually slid over the block, means to hold the cylinder with the block during the blocking operation, and means to relieve said holding means for removal of the cylinder and the strip after the latter has been blocked.

42. In a blocking device adapted to wind a strip coming from a strip mill, the combination of a rotatable block, guiding means between the mill and the block, and longitudinal openings in said guiding means for the purpose set forth.

43. In a blocking device adapted to wind a strip coming from a strip mill, the combination of a rotatable block, guiding

means, comprising an upper and a lower guide for guiding the strip, and openings in said guiding means for the purpose set forth.

44. In a blocking device adapted to wind a strip coming from a strip mill, the combination of an upper and a lower guide member constructed to permit the escape of oil and water from the strip and to keep the strip in sight in its travel from the mill to the block through the guides.

45. In a blocking device adapted to wind a strip coming from a strip mill, the combination of a rotatable block and guiding means for the strip between the mill and the block consisting of a plurality of bars fastened together to form a grill structure for the purpose set forth.

46. In a blocking device adapted to wind a strip coming from a strip mill, the combination of a rotatable block, guiding means for the strip between the mill and the block, knife blades supported on said guiding means, means for forcing these blades in contact with the mill rolls, and means to shift said knife blades longitudinally of the mill rolls independently of the guiding means.

47. In a blocking device adapted to wind a strip coming from a strip mill, the combination of a rotatable block, guiding means for the strip between the mill and the block, knife blades in forced contact with the mill rolls, said knife blades being less in width than the guiding means, and means to adjust these blades longitudinally of the end of the guiding means and the mill rolls.

48. In a blocking device adapted to wind a strip coming from a strip mill, the combination of a rotatable block, guiding means between the mill rolls and the block, knife blades for scraping the sheet loose from the mill rolls and conveying the same to the guiding means, means to shift the knife blades parallel with the mill rolls and the end of the guiding means, said knife blades being yieldingly connected with the guiding means.

49. In a blocking device adapted to wind a strip coming from a strip mill, the combination of a rotatable block, guiding means between the mill rolls and the block, knife blades under pressure against the mill rolls for scraping the sheet loose from the mill rolls and conveying the same to the guiding means, means to shift the knife blades parallel with the mill rolls and the end of the guiding means, said knife blades having a yielding connection with the guiding means.

50. In a blocking device adapted to wind a strip coming from a strip mill, the combination of a rotatable block, guiding means between the mill rolls and the block, knife blades in forced contact with the mill rolls, said knife blades being less in width than

the guiding means, and means manually operable for shifting said knife blades and for automatically holding said knife blades in position, at a desired point across the face 5 of the mill rolls.

51. In combination, a rolling mill, a block 10 for blocking strip metal fed from the mill, means for rotating the block, guiding means for the strip, means operable by the rolls of the mill for attaching the strip to the block, and a separate means for maintaining the strip attached to the block and operable at the instant the strip is so attached to simultaneously neutralize the action of the first 15 named means and withdraw the guides from operative position.

52. In a blocking device adapted to wind a strip coming from a strip mill, the combination of a rotatable block, guiding means 20 for the strip between the mill and the block, knife blades coacting with said guiding means and in contact with the mill rolls, and means to shift said knife blades independently of the guiding means longitudinally of the mill rolls.

53. In a blocking device adapted to wind a strip coming from a strip mill, the combination of a rotatable block, guiding means for the strip between the mill and the block, 30 and additional guiding means adjustable independently of the first-named guiding means and longitudinally of the mill rolls.

54. In a blocking device adapted to wind a strip coming from a strip mill, the combination of a rotatable block, guiding means for the strip between the mill and the block, comprising an upper and a lower guiding member, a yieldable extension on the lower guiding member controlled by the upper 40 guide member.

55. In a blocking device adapted to wind a strip coming from a strip mill, the combination of a rotatable block, a member carrying the same, a strip receiving space being left between said supporting member and the block, guiding means for the strip between the mill and the block, and means to vary the size of the space between said supporting member and the block to accommodate the latter to strips of varying thickness.

56. In a blocking device adapted to wind a strip coming from a strip mill, the combination of a rotatable block comprising

two members, one of which is entirely removable from the other, means for holding one member stationary while the other is rotating, and means automatically to relieve said holding means to cause both members to rotate as a unit.

57. In a blocking device adapted to wind a strip coming from a strip mill, the combination of a rotatable block comprising two members movable independently of each other, means for holding one member stationary while the other is rotating, and means operable by said stationary member to relieve said holding means to permit both members to rotate as a unit.

58. In a strip mill, the combination of 70 blocking mechanism, guiding means between the strip mill and said blocking mechanism, and an offset supporting means for said guiding means about which the guiding means may be actuated to remove them 75 from between the strip mill and said blocking mechanism.

59. In a strip mill, the combination of 80 blocking mechanism, guiding means between the strip mill and said blocking mechanism, additional guiding means adjacent the rolls of the strip mill and movable relative to said first named guiding means, and supporting means for all of the said guiding means independent of the blocking mechanism, whereby the guiding means may be swung to a position not adjacent the mill rolls.

60. In a strip mill, the combination of 90 blocking mechanism, guiding means between the strip mill and said blocking mechanism, additional flexible guiding means adjacent the rolls of the strip mill and adjustable relatively to said first named guiding means, supporting means for all of the guiding 95 means and independent of the blocking mechanism whereby the guiding means may be swung to a position not adjacent the mill rolls, and means for moving said first named guiding means independently of the second 100 named guiding means.

In testimony whereof, I have signed my name to this specification in the presence of two subscribing witnesses.

AUGUST SUNDH.
